CLAIM

The ornamental design for a handheld tester, as shown and described.

DESCRIPTION

FIG. 1 is a perspective view of a handheld tester according to our design;

FIG. 2 is a top plan view of the handheld tester;

FIG. 3 is a bottom plan view of the handheld tester;

FIG. 4 is a left-side view of the handheld tester;

FIG. 5 is a right-side view of the handheld tester;

FIG. 6 is a front view of the handheld tester;

FIG. 7 is a rear view of the handheld tester; and,

FIG. 8 is a rear view of the handheld tester according to an alternate embodiment.

The broken lines in the figures show portions of the handheld tester that form no part of the claimed design.
